SURFACE BROACH

John A. Markstrum, Detroit, Mich., assignor to
Ex-Cell-O Corporation, Detroit, Mich., a corporation of Michigan

Application June 26, 1942, Serial No. 448,597

11 Claims. (Cl. 29—95.1)

The present invention relates to improvements in surface broaches and has particular reference to a broach adapted to take a progressive cut laterally across a work surface.

One of the objects of the present invention is to provide a novel surface broach comprising a plurality of similar broach sections adapted to be removably secured as inserts to a slidable support.

Another object is to provide a new and improved surface broach of the sectional type in which spaced sections are arranged to cut in opposed relation from opposite sides toward the center of the work surface.

A further object is to provide a novel surface broach comprising a slidable support, and a broach section adapted to be removably secured thereto in initial and reversed positions so that when one longitudinal side is dull, the section may be reversed to locate the other longitudinal side in cutting position, thereby doubling the cutting life of the section.

A general object of the invention is to provide a novel surface broach which is simple in construction, and economical to set up and maintain.

Other objects and advantages will become apparent as the description proceeds.

In the accompanying drawings,

Figure 1 is a plan view of a broach embodying the features of my invention.

Fig. 2 is an end view of the broach shown in operative relation to a work part.

Fig. 3 is a fragmentary perspective view of one of the broach sections.

Fig. 4 is a plan view of a modified form of broach.

Fig. 5 is an end view of the broach shown in Fig. 4.

Fig. 6 is a fragmentary sectional view taken substantially along lines 6—6 of Fig. 4.

Referring more particularly to the drawings, the broach comprises a slidable support 7 of rectangular form adapted to be connected to the ram (not shown) of the broaching machine for longitudinal movement from left to right in Fig. 1. A plurality of identical broach sections 8 (Fig. 3) are removably mounted as inserts on the support 7 in predetermined arrangement, depending on the requirements of the broaching operation to be performed. In the present instance, each of the broach sections 8 consists of a rectangular bar having flat parallel side surfaces 9 and 10, and a flat bottom surface 11. The top surface of the section 8 is formed with a longi-

tudinal series of suitably relieved broach teeth 12 separated from each other by clearance spaces 13, and extending crosswise of the section. More particularly, each tooth 12 has a top edge 14, and is chamfered at opposite ends to provide oppositely inclined side cutting edges 15 and 16. The successive teeth 12 are arranged to take a progressive series of parallel cuts. In the present instance, the cutting offset is obtained by 10 inclining the broach section 8 at a suitable angle to the direction of movement of the support 7 in the broaching operation. Consequently, the teeth 12 can be made, and preferably are made, of uniform height and width, and with a uniform and symmetrical cutting contour. By laterally inclining or orientating the broach section 8 to the plane of the support 7 at the angle of the chamfer on the ends of the teeth 12, one series or the other of the side cutting edges 15 and 16 is disposed in cutting position. If, for example, the cutting edges 15 are disposed in cutting position, lateral reversal of the angularity of the broach section 8 will dispose the cutting edges 16 uppermost in position to cut the work.

The broach sections 8 may be selected and arranged to provide different forms of composite broaches. In Figs. 1 to 3, four series of broach sections are provided and are arranged in pairs 30 of opposed sections to cut from opposite sides toward the center of two surfaces S on a work-piece W, the plane of cut being indicated by the dotted line 17.

The broach sections 8 may be mounted on the support 7 in any suitable manner to present the cutting edges to the work. In the present instance, the support 7 is formed in the top surface with four longitudinal grooves 18, 19, 20 and 21 of angular form. The two outermost 35 grooves 18 and 21 converge toward each other from the leading to the trailing end of the support 7. The two innermost grooves 19 and 23 diverge from each other and converge with the respective outermost grooves from the leading 40 toward the trailing end of the support, and are somewhat shorter than the outermost grooves to provide an overlap.

Each of the grooves 18 to 21 is suitably shaped to support the broach sections 8 in a tilted cutting position with one set or the other of the side edges 15 and 16 disposed uppermost and parallel to the top surface of the supporting slab 8. In the present instance, each groove is V-shaped, with sides 22 and 23 extending at 55 right angles to each other, and laterally orien-

tated as required by the angularity of the side cutting edges 15 and 16 of the broach sections. Consequently, one side 22 of each groove provides a solid backing surface, and the other side 23 provides a clamping surface for the broach sections.

The broach sections 8 are secured, as by means of bolts 24, in series relation in each of the mounting grooves 18 to 21. The longitudinal inclination of the sections 8 provides the lateral cutting offset of the successive teeth 12 of each series, and the number of sections provided in each series is dependent on the desired width of cut within the limits of the ram stroke. In the present instance, three sections 8 are disposed in each of the outermost grooves 18 and 21, and two sections are disposed in the innermost grooves 19 and 20. The sections in the grooves 18 and 19, and also those in the grooves 20 and 21, are tilted oppositely and suitably spaced to cut from opposite sides toward the center across the respective work surfaces S. The trailing section of each outer series of sections overlaps the range of cut of the associated inner series of sections, and hence serves to remove the narrow fin or rib of stock which remains after the oppositely disposed sections have completed their cuts.

A conventional type of surface broach section 25 in the form of a slab may be mounted on the trailing end of the support 7 to produce the final size and finish on the work W. The broach section 25 has a series of transverse cutting edges 26 which are of progressively increasing height from the leading to the trailing end of the slab, and is of such width that it extends across the aggregate range of the preceding series of broach sections 8.

In operation, and referring particularly to Figs. 1 and 2, the support 7 is translated longitudinally along the work W to be broached. Initially, the pairs of opposed leading broach sections 18 and 19, and 20 and 21, start the broaching cut from opposite side edges toward the center of the respective surfaces S along the plane 17. In the continued translation of the support 7, the intermediate pairs of opposed broach sections 18 and 19, and 20 and 21 continue the broaching cut, and leave only a narrow fin or rib of stock at each of the spaces 27. The third or trailing sections 18 and 22 then serve to remove the final stock to complete the cut across the work W. When provided, the conventional broach section 25 serves to take a finish cut on the surfaces S.

It will be evident that all of the broaching sections 8 are alike in form, and adapted for interchangeable use. They may be selected and arranged to provide composite broaches of different forms depending on the requirements of the work. They are interchangeable from one groove to another so as to cut from one side or the other of the work, and as a result, one series of side cutting edges 15 may be used until dulled, and then the other series of cutting edges 16 may be used. As a consequence, the cutting life of each broach section is doubled, and in general the composite broach is economical to set up and to maintain.

The form of broach illustrated in Figs. 1 to 3 is especially adapted for broaching work surfaces S of comparatively narrow width which can be broached within the available stroke of the support 7 merely by two cuts starting at opposite side edges of the surface. When the work surface, such as the surface S₁ of the work

W₁ of Fig. 5, is so wide that, within the available stroke of the support, two cuts respectively from opposite sides are insufficient to broach the entire surface, the broach sections may be arranged as illustrated in a modified form of broach, as shown in Figs. 4 to 6. This form is generally similar to the form of Figs. 1 to 3, and like parts are therefore identified by the same reference numerals plus the letter a.

The support 7^a is formed with two longitudinally inclined grooves 20^a and 21^a which are spaced further apart than the grooves 20 and 21 of Fig. 2, but which in every other respect correspond to the latter. Two series of broach sections 8^a are removably secured by means of bolts 24^a against the oppositely inclined mounting surfaces 23^a. It will be evident that the two series of broach sections thus mounted in the grooves 20^a and 21^a will cut from opposite side edges toward the center of the work surface S₁ along the cutting plane 17^a.

Mounted in a vertical rectangular groove 23 in the leading end of the support 7^a between the leading pair of opposed broach sections 8^a is an upright broach section 29 extending parallel to the path of movement. The top of the broach section 29 is formed with a longitudinal series of broach teeth 30 of progressively increasing cutting amplitude from the leading toward the trailing end so as to form a longitudinal starting groove 32 in the intermediate portion of the work surface S₁. The section 29 may be the same in form as the sections 8^a, but with the trailing end elevated to provide the progressive cutting amplitude.

Also formed in the support 7^a, intermediate the grooves 20^a and 21^a and trailing the groove 28, is an inclined groove 33 similar in form and parallel to the trailing portion of the groove 21^a. A series of broach sections 8^a are removably mounted in the groove 33, and in operation act to cut from the groove 32 formed by the broach section 29 across the work surface S₁ outwardly toward the groove 20^a.

The last trailing sections 8^a in the grooves 21^a and 33 respectively overlap the cutting range of the broach section 29 and the trailing broach section 8^a in the groove 20^a so that the surface S₁ is completely traversed in the broaching operation. In the continued movement of the support 7^a, the broach section 25^a is adapted to cut the surface S₁ to the final depth and finish.

I claim as my invention:

1. A surface broach comprising, in combination, a rectilinearly movable support, an elongated broach section removably mounted on said support and having a longitudinal series of transverse teeth of uniform height and width extending completely across the body of said section and chamfered at opposite ends to provide oppositely inclined side cutting edges and intermediate top cutting edges, and means for securing said section to said support in a longitudinally inclined position and laterally tilted at the angle of said side cutting edges to present one set or the other of said side cutting edges of said series of teeth to the work.

2. A surface broach comprising, in combination, a rectilinearly movable support, an elongated broach section removably mounted on said support and having a longitudinal series of transverse teeth extending across the body of said section and chamfered at opposite ends to provide oppositely inclined side cutting edges, and means for securing said section to said support with the

successive teeth disposed in offset relation longitudinally of said support and tilted laterally at the angle of said cutting edges so as to dispose selectively one series or the other of said side cutting edges uppermost in cutting position.

3. A symmetrical surface broach section comprising a longitudinal bar of rectangular transverse form having flat parallel sides and a flat perpendicular bottom surface, and formed along the top with a single longitudinal series of relieved transverse broach teeth of uniform height, width and cutting contour extending laterally across the top of said bar in parallel relation to said bottom surface, the longitudinal axis of symmetry of said series of teeth being parallel to said sides, the ends of said teeth being symmetrically chamfered to provide inclined side cutting edges of equal but opposite degree and intermediate top cutting edges.

4. A surface broach comprising, in combination, a rectilinearly movable support having laterally spaced mounting surfaces oppositely inclined both laterally and longitudinally, and a plurality of elongated broach sections removably mounted on said surfaces and having on the top a longitudinal series of relieved teeth of uniform height and width, said broach teeth having a symmetrical cutting contour with cutting edges along the sides of each section oppositely inclined to the tops at the angle of said mounting surfaces, and means for securing said sections interchangeably to said support.

5. A surface broach comprising, in combination, a rectilinearly movable support, a pair of opposed broach sections removably secured in laterally spaced relation to said support, said sections being oppositely inclined longitudinally of the direction of movement to converge symmetrically toward each other from the trailing toward the leading end, and being alike in form, each broach section having a longitudinal series of teeth of uniform height and width and with oppositely inclined side cutting edges, and means for securing said sections removably and interchangeably to said support, said sections being laterally inclined toward each other to present the outermost side cutting edges uppermost in position respectively to cut from the outer edges of a work surface toward the center thereof, whereby interchanging said sections in position on said support will interchange the location in cutting position of the side cutting edges of each section.

6. A surface broach comprising, in combination, a rectilinearly movable support formed with grooves converging longitudinally toward each other from the leading to the trailing end, and having inclined mounting surfaces of equal but opposite degree relative to the plane of cut, a series of like broach sections removably secured in end to end relation within said grooves, each section having a longitudinal series of teeth of uniform height and width and with oppositely inclined side cutting edges, and means for securing said broach sections interchangeably against said mounting surfaces, whereby first one series and then the other series of said side cutting edges of each section may be located in cutting position.

7. A surface broach comprising, in combination, a movable support formed in the top with a longitudinally inclined V-groove having a backing surface and a clamping surface arranged at right angles to each other, an elongated broach section having a bottom surface adapted to en-

gage said backing surface and a side surface adapted to be positioned against said clamping surface, said broach section having on the top a single longitudinal series of relieved teeth with oppositely inclined symmetrical cutting edges along opposite sides and intermediate cutting edges along the top, said groove being laterally orientated so that one series of side cutting edges will be disposed uppermost in cutting position.

10. 8. A surface broach comprising, in combination, a rectilinearly movable support formed with a pair of laterally spaced longitudinally inclined mounting grooves converged toward each other from the leading toward the trailing end, each

15 of said grooves being right angled in transverse form to present a backing surface and a clamping surface, the clamping surfaces of said grooves being laterally inclined toward each other at the same but opposite degree, an elongated broach

20 section adapted to be selectively mounted in either of said grooves, said section being rectangular in transverse form and having a bottom surface adapted to seat against said backing surface and having parallel side surfaces adapted selectively to seat against said clamping surface of the selected groove, said section being formed with a longitudinal series of broach teeth of uniform height and cutting contour with oppositely inclined cutting edges along opposite sides, and

25 30 means for removably securing said broach section selectively against the clamping surface of either of said grooves, whereby one or the other of said series of inclined cutting edges may be disposed in cutting position to cut from either side of the work.

9. A surface broach comprising, in combination, a rectilinearly movable support formed with a pair of laterally spaced longitudinally inclined mounting grooves converged toward each other at

40 from the leading toward the trailing end, each of said grooves being right-angled in transverse form to present a backing surface and a clamping surface, the clamping surfaces of said grooves being laterally inclined toward each other at

45 the same but opposite degree, a plurality of elongated broach sections adapted to be selectively mounted in said grooves, each section having a bottom surface adapted to seat against the backing surface and parallel side surfaces adapted selectively to seat against the clamping surface of the selected groove, and being formed with a longitudinal series of broach teeth with oppositely inclined cutting edges along opposite sides, and means for removably securing said broach

50 55 sections selectively and interchangeably against the clamping surfaces of said grooves, whereby one or the other of said series of cutting edges of each section may be disposed in cutting position.

10. A surface broach comprising, in combination, a rectilinearly movable support, a plurality of broach sections removably and interchangeably secured in laterally opposed and series relation on said support, and each being formed with a longitudinal series of broach teeth, certain of said sections being inclined laterally and longitudinally of the line of cut and converging in series from the leading toward the trailing end to cut from opposite sides toward the center of the work surface, and an intermediate series of

60 65 70 broach sections mounted on said support, the leading section of said intermediate series extending parallel to the line of cut to form a starting groove, and the trailing section of said intermediate series being spaced from and parallel to

75 one of the outermost series of broach sections to

cut laterally across the work surface from said groove toward the other outermost series of broach sections.

11. A surface broach comprising, in combination, a longitudinal movable support, a longitudinal broach section secured on said support and having a series of broach teeth of progressively increasing amplitude for cutting a starting groove in the work surface, a longitudinally inclined broach section mounted on said support in lateral spaced relation to said first mentioned

section and adapted to cut from one side toward the center of the work surface, trailing broach sections secured in laterally spaced relation to said support in series respectively with said first mentioned sections, and converging toward each other from the leading toward the trailing end, and a longitudinally inclined broach section secured to said support and arranged to cut across the terminal area left by said last mentioned sections.

JOHN A. MARKSTRUM.
